UNITED STATES PATENT OFFICE.

THOMAS S. COBB, OF MIAMI, FLORIDA.

DUST EXTRACTOR.

Application filed March 18, 1925. Serial No. 16,477.

My invention relates to apparatus for removing dust, dirt and similar impurities from cotton, hair, or like material which is being handled in mass. The object of the 5 invention is to provide a simple and inexpensive apparatus which will operate automatically to deliver the cotton or other material at a point of use and withdraw therefrom during its passage all impurities 10 so that the material delivered for use will be clean and in suitable condition to produce a sanitary article. The apparatus is particularly advantageous in mattress factories or similar establishments. The stated 15 objects of the invention, and other objects which will incidentally appear, are attained in such an apparatus as is illustrated in the accompanying drawing, and the invention resides in certain novel features which will 20 be particularly pointed out in the appended claims.

In the drawing:—

Figure 1 is a plan view, partly broken away and in horizontal section, of one embodiment of my invention, and

Fig. 2 is a vertical section on the line 2—2 of Fig. 1.

In the drawing, the reference numeral 1 indicates a delivery spout which may be the 30 outlet of a cotton gin or the like and may be equipped with a fan or blower of any approved form mounted in any approved manner, as indicated conventionally at 2. Connected with the spout 1 so as to align 35 axially therewith and receive material directly therefrom is a pipe or conduit 3 which will have the same cross sectional contour as the spout 1 so that it will readily fit thereto. The spout 3 is constructed with two 40 branches 4 and 5, as shown clearly in Fig. 1, one of the branches being alined with the main body of the conduit, while the other forms an acute angle with the main body so as to extend laterally therefrom but 45 at such an angle thereto as to furnish an easy turn for the material flowing through the conduit. In the top and bottom of the conduit at the junction of the branches 4 and 5 grooves or beads 6 are formed and in 50 the said grooves or beads is slidably fitted a screen 7 which may conveniently be formed of wire netting having its edges fitted in a frame or binding 8 adapted to fit cloosly in the grooves and maintain the shape of the screen. At one end the frame or binding 55 8 is provided with a cover 9 adapted to

extend over the opening in the side of the conduit through which the screen is inserted and thereby form a close practically airtight joint therewith. A knob or other 60 handle 10 is provided on the cover 9 to facilitate the handling of the screen. The branch conduit 4 extends, in the illustrated embodiment of the invention, a short distance from the straight branch 5 and is then given 65 a slight turn to form a conduit 11 extending parallel with the branch conduit 5. This conduit 11 may be carried to any point in the factory where it is desired to deliver the material. A supplemental branch air conduit 12 communicates with the conduit 11 through the side of the same at the junction thereof with the conduit 4, and a screen 13, corresponding in all respects to the screen 7, is fitted in the conduit 4 in alignment with that wall of the conduit 11 more remote from the conduit 5. Beyond the 70 screen 13, the conduit 12 is formed with a return bend, as indicated at 14, and is carried to and merges into the conduit 5, as 75 shown at 15. The conduit 5 may be carried to any desired point and may conveniently be extended through the wall of the building so that the impurities traveling therethrough will be delivered outside the building. In each conduit 5 and 12 is formed an 80 offset 16 whereby clearance between the air conduits and the material conduit 11 is attained, as will be readily understood upon reference to the drawing.

It is thought the operation of my device will be readily understood from the foregoing description, taken in connection with the accompanying drawing. The cotton, hair or material of whatever nature is delivered 95 from the forming machine into the conduit 3 under the influence of the blower 2 with considerable force and will impinge against and be turned aside by the screen 7, the greater portion of the dust and other impurities passing through the screen into the conduit 5. The partly cleaned material will then impinge against the screen 13 and again be deflected so that it will flow through the conduit 11 to the point of delivery. The screen 13 will, of course, serve not only as a deflector for the material but will also separate an additional quantity of dust and dirt from the material so that the material flowing through the delivery conduit 11 will 100 be in proper condition for use. The apparatus is very simple in construction and may 105 110

be installed in any factory at a slight expense. The screens are easily removable when it is necessary to clean them of accretions, and the invention may be embodied in an apparatus having only one screen or any desired number of screens. Other variations in the specific details may be made without involving any departure from the invention as the same is defined in the following claims. For instance, the blower may be arranged at any point in the apparatus as may be most convenient under any given circumstances, and while I have stated that the device is applied to the delivery spout of a cotton gin, it may obviously be connected with other machines without involving any substantial changes in construction or operation. By disposing the screens obliquely across the path of the flowing material to be treated, the material is easily turned aside so that loss due to particles adhering to the screen will be minimized and at the same time the material is permitted to impinge upon the screens with sufficient force to partly loosen the dust and dirt which, of course, will pass through the screen under the influence of the air blast.

It will be understood, of course, that the illustration of the blower 2 is merely by way of example, inasmuch as frequently the force of the blast through the cotton gin,

or other machine to which the dust extractor is attached, is sufficient to drive the material through the cleaning conduits and additional power is unnecessary.

Having thus described the invention, I claim:

1. An apparatus for the purpose set forth comprising a conduit for the passage of material to be cleaned, a conduit for the passage of impurities removed from the material communicating with and arranged at an angle to the first-mentioned conduit, and a screen slidably engaged in the first-mentioned conduit in alinement with a wall of the second-mentioned conduit and extending obliquely across the first-mentioned conduit.

2. An apparatus for the purpose set forth comprising a conduit to receive material to be cleaned, branch conduits communicating therewith, one of said conduits being alined with the first-mentioned conduit and the other branch conduit being disposed at a slight angle thereto, and a screen disposed obliquely across the conduit for the impurities and slidably engaged therein, the two branch conduits having delivery portions arranged in parallelism and the conduit for the impurities having an offset whereby to clear the conduit for the material.

In testimony whereof I affix my signature.

THOMAS S. COBB. [L.S.]
